F. C. BARGAR

FIRE EXTINGUISHING APPARATUS

Filed April 8, 1921

UNITED STATES PATENT OFFICE.

FREDERICK C. BARGAR, OF COLUMBUS, OHIO, ASSIGNOR TO NU-EX-FIRE APPLIANCE COMPANY, OF COLUMBUS, OHIO, A CORPORATION OF DELAWARE.

FIRE-EXTINGUISHING APPARATUS.

Application filed April 8, 1921. Serial No. 459,573.

To all whom it may concern:

Be it known that I, FREDERICK C. BARGAR, a citizen of the United States, and resident of Columbus, in the county of Franklin and State of Ohio, have invented certain new and useful Improvements in Fire-Extinguishing Apparatus, of which the following is a specification.

My invention relates to fire extinguishing apparatus and more particularly to apparatus of the type in which fire extinguishing medium or charge normally stored in suitable containing means, as a tank or receptacle, is forcibly ejected therefrom in time of fire in a jet or stream, a gas generator adapted to deliver gas to the containing means and which may be located in the receptacle being utilized for creating an ejecting pressure; and has special reference to the provision of such an extinguisher in which the ejecting pressure is provided by gases generated as the result of combustion of a suitable combustible substance, my present invention constituting an improvement of my fire extinguishing apparatus disclosed and claimed in my co-pending application, Serial Number 316,749, filed August 11, 1919, now Patent No. 1,422,406, dated July 11, 1922.

The principal objects of my invention comprehend the provision of improved fire extinguishing apparatus of the type referred to and of an improved fire extinguisher operating as above indicated and whose simplicity of construction affords greater facility and increased safety in handling the extinguisher and more particularly in assembling the parts of the extinguisher and in inspecting and using the same, the parts of the extinguisher being so arranged and functioning in such manner as to yield a greater efficiency in use.

To the accomplishment of the foregoing and such other objects as may hereinafter appear, my invention consists in the elements and their relation one to the other, as herein-after particularly described and sought to be defined in the claims, reference being had to the accompanying drawings which show a preferred embodiment of my invention and in which

Figure 1 is an elevational view in cross section of my novel fire extinguishing apparatus,

Figure 2 is an elevational view of the same

in inverted position with parts broken away to show the operation of the gas generator,

Figure 3 is a cross sectional view of a novel type of gas generating cartridge used in my extinguisher,

Figure 4 is a sectional view of the same on the line 4—4, Figure 3, and

Figure 5 is an enlarged cross sectional view of the same on the line 5—5, Figure 3.

Referring to the drawings, I have shown my invention preferably embodied in an extinguisher of the invertible type, although it will be apparent that my invention may be applied to other types of extinguishers. My invention contemplates the utilization and adaptation of present standard fire extinguisher equipment and to this end I have shown my invention as applied to a hand extinguisher of a well known type. This extinguisher comprises an outer shell or receptacle, having a cylindrical body wall 10, a dished bottom 11 and a dome top 12, a cylindrical end supporting stand 13 being provided and preferably made integral with the cylindrical body portion 10. The extinguisher is supplied with the usual threaded neck 14 connected to the dome portion 12, as by being soldered to the interior walls thereof as at 15, the usual hand wheel 16 being provided having a threaded flange 17 received by the threaded neck 14, a gasket 18 being supplied between the hand wheel and the threaded neck for the purpose of securing an effective closure between these elements. Connected for communication with the outer receptacle 10 is the usual discharge pipe 19 for the fire extinguishing medium, to which is connected the usual hose 20, carrying at an end thereof the nozzle 21. The outer receptacle 10 is intended for the reception of a fire extinguishing charge which may consist of a solution of calcium chloride in water, this solution having a low freezing point, the extinguisher being thus adapted to be used under all climatic conditions.

For the purpose of expelling or ejecting the fire extinguishing medium or charge from the outer receptacle 10 in time of fire, I provide a gas generator mounted within the said outer receptacle 10. The gas generator of my present invention comprehends the utilization of a combustible material adapted to be ignited the gases of combustion being thereupon utilized to exert operat-

- ing pressure on the level of the extinguishing medium to drive the same steadily from the extinguisher in a continuous stream onto the fire. For the purpose of housing and sealing the combustible charge from the fire extinguishing medium and for the purpose of providing a gas generating chamber, I replace the usual inner tube used in the standard type of extinguisher by an inner receptacle 22 of novel construction, the said receptacle 22 comprising a simple tubular section provided at the top end thereof with a flanged ring 23, the flange of which is adapted to seat on a shoulder 24 of the neck 14, the inner tube 22 being thus adapted to be hung in the outer receptacle 10 from the top of the said receptacle; the said inner tube being provided with a bottom 25 of any desired construction, the form shown in the drawings comprising a cap threaded onto the bottom end of the tubular section 22. It will be noted that the top surface of the flanged ring 23 is flush with the top surface of the threaded neck 14, the closure provided by hand wheel 16 and gasket 18 cooperating with these parts to effectively close the inner receptacle and seal the same from the fire extinguishing medium in the outer receptacle 10.
- Housed in the inner receptacle 22 is a movable cartridge 26, the said cartridge being located preferably in the bottom of the receptacle 22 and being adapted to gravitate from this position towards the top of the extinguisher upon inversion of the same. For the purpose of simplifying the construction of the extinguisher and rendering the same subject to greater safety and surety of operation, I have found it desirable to modify the cartridge shown in my copending application above referred to and to combine the cartridge and the weight cooperating therewith into a single unit. To this end I have provided a cartridge as shown in Figures 3 to 5 of the drawings, said cartridge comprising a tubular enclosing shell 27, the said shell enclosing a combustible material and weights associated therewith. By combining the weights and the combustible material into a single unit, and eliminating the use of a separate weight, the possibility of the weight being left out when assembling the parts of the apparatus is entirely done away with. Furthermore, the weights serve to give force to the drop of the cartridge upon inversion of the extinguisher, thus aiding in minimizing the liability of a misfire. Moreover the weights in the cartridge serve as part of the firing mechanism, as will become clearer hereinafter.
- It has been found desirable to so construct the cartridge 26 that it may be inserted in the inner receptacle 22 with either end uppermost, so that it may be fired from either end, this construction also permitting facility in assembly and use. It has been further found desirable to so construct the cartridge that it may be handled with greater safety and in fact be dropped into the receptacle 22, and dropped out of the receptacle in times of inspection without any chance of a misfiring taking place. To this end I have provided a reversible cartridge having a symmetrical arrangement, the said cartridge having weighted elements 28 located at opposite ends thereof, the said weighted elements being preferably hollow elements for a purpose to appear hereinafter. Located interiorly and centrally of the cartridge are fuses 29, which may consist, for example, of gun powder, the said fuses being of simple tubular construction and having longitudinal vents 30 for the purpose of facilitating burning thereof. Each of the fuses 29 is provided with a sheath or wrapper 31, an end of each fuse being exposed beyond the said wrapper, the wrapper 31 having an asbestos base and functioning to control gradual cartridge combustion. I preferably include two such fuses in the cartridge, the exposed end of one fuse facing in a direction opposite to the exposed end of the other, as clearly shown in Figure 3 of the drawings. Adjacent the exposed end of each fuse I provide a charge of small firing powder 32, this firing powder being held in position up to the time of firing by means of screens 33, the said screens 33 being also utilized to hold a part of the powder train such as at 34, the screens 33 further performing the function of preventing the first gases generated from blowing part of the small powder away before it is ignited.
- For the purpose of firing the powder to generate the pressure gases in time of fire, I provide a simple firing equipment which comprises an ignition system mounted at each end of the cartridge and located preferably within the core of each hollow weighted member 28. The firing equipment or ignition system preferably comprises a metallic casing 35 open at both ends, ignition elements 36 being received in the opposite open ends of the casing 35, these ignition elements comprising preferably blocks of wood appropriately bored for the reception of match heads 37, a plurality of these match heads being mounted in each block 36 for the purpose of increasing assurance of ignition in time of fire. The blocks 36 are loosely mounted in the casing 35 and are urged outwardly in opposite directions by means of compression springs 38, opposite ends of which, encircle the match sticks and are retained in position in enlarged bores 39 formed in each of the blocks 36. As heretofore referred to, these elements comprising the ignition system are located in the

core of each of the weights 28 and for the purpose of fixedly locating this ignition system within the cores of weights 28, I preferably provide opposed channels 40 contoured to receive the opposed resiliently urged match heads 37, the channels 40 being preferably faced with an abrasive material 41 such as emery, this construction minimizing failure of ignition in time of fire. For 10 the purpose of still further assuring ignition and for the purpose of fixedly mounting the match heads 37 in the blocks 36, I preferably imbed the match heads in a black powder paste 42, as shown clearly in Figure 15 5 of the drawings. In order to facilitate outflow of the generated gases the weights 28 are preferably provided in the circumference thereof with a series of spaced vents 43 running longitudinally of the weights, as 20 clearly shown in the drawings.

The tubular shell 27 enclosing the fuse and weight elements hereinabove described is closed on opposite ends thereof by means of flanged annular members 44 suitably connected to the shell 27, as by being soldered thereto, these flanged members 44 providing enlarged central openings, soft metal plates or diaphragms 45, made, for example, of sheet lead, overlying the openings and 25 connected to the members 44 as by being brazed thereto. The plates 45 are slightly spaced from the firing casing 35 at each end of the cartridge as shown particularly in Figure 3 of the drawings, this spacing being 30 provided for the purpose of preventing any firing except by the forcible injection or insertion of a firing pin or other element through either of the opposite ends of the cartridge. I have found that such a construction may be handled with great safety, these cartridges being freely thrown about without the occurrence of a misfire. It will 40 be apparent that the cartridge 26 embodying the above described elements may be fired from either end by breaking through the soft metal disk 45 and forcing the ignition system further down the core of the weighted members 28. This cartridge 26 has been found to be subject to simplicity of 50 manufacturing operations and to afford ease of assembly. Thus the simple type fuses 29 may be dropped into position in the cartridge shell, the weighted members 28 being then inserted with the interposition of the screens 33 and the small powder 32, the ignition system being then inserted in the cartridge shell, the ends of the cartridge shell being then closed by the plate 45. The cartridge as a whole may then be dropped with 55 either end uppermost in the inner receptacle 22, when the parts of the apparatus are assembled.

The cartridge and weight unit 26 is placed in the bottom of the receptacle 22 as hereinabove referred to, the cartridge being adapt- 60 ed to be fired upon inversion of the apparatus. For the purpose of firing the cartridge upon inversion of the apparatus, I provide a firing pin 46 mounted independently of the inner receptacle 22, the said firing pin 70 being in the form of a harpoon and having a plurality of cutting edges 47. As will be apparent, upon inversion of the apparatus, the combined cartridge and weight 26 will 75 forcibly gravitate into impacting contact with the firing pin 46, the cutting edges 47 severing the frangible diaphragm or soft metal plate 45, further movement of the cartridge and weight unit 26 effecting impact between the firing pin 46 and the ignition system 35, the ignition system being forced into the core of the weight 28 for igniting the powder and the fuses. For the purpose of limiting the movement of the cartridge 26, I provide a supporting cross 80 rod 48 received in a bore of the firing pin 46.

As hereinabove indicated the firing pin 46 is mounted independently of the inner receptacle 22, this construction being provided to the end of securing an extinguisher 85 affording greater safety in assembling and general handling. I preferably mount the firing pin 46 on the hand wheel 16, as clearly shown in the drawings, this permitting the use of a unitary hand wheel and firing pin. 90

It will be apparent that with such a construction, upon removal of the hand wheel for purposes of inspection or recharging of the device for example, the firing pin or harpoon 46 will be simultaneously removed therewith, subsequent removal of the inner receptacle and inverting the same to remove cartridge 26 not subjecting the cartridge to firing operation. It will also be apparent 95 from this construction that in assembling the device there is no possibility of connecting the harpoon or firing pin 46 to the inner receptacle 22 before inserting the inner receptacle in the extinguisher, this preventing any possibility of misfire during assembling of the parts. It has been found that 100 this construction provides a maximum of safety in assembling, inspection and in use.

For the purpose of preventing the cartridge and weight system 26 from sliding down the inner receptacle 22 when the apparatus is tilted, and for the purpose of affording a forcibly gravitated movement of the cartridge, I provide restraining means 105 in the path of the cartridge normally operative to prevent movement of the cartridge, but permitting movement of the same when the extinguisher is inverted to substantially erect or vertical position. To this end I provide an annular depression 49, as clearly 110 shown in Figure 1 of the drawings, the said depression cooperating with the tubular cartridge 26 to restrain movement of the same until the device is substantially completely inverted.

Upon inversion of the apparatus and firing of the cartridge 26 the fuses are ignited and undergo slow combustion for the generation of the required gases, which escape through the cartridge and quickly fill the inner receptacle or chamber 22. Means is provided for conducting these gases from the chamber 22 and into the outer receptacle 10 to exert operating pressure on the level of the fire extinguishing charge therein. To this end I have provided a port 50 serving as the means of gas communication between the inner receptacle 22 and the outer receptacle 10. I have found that the gases of combustion, in moving from the inner receptacle to the top of the extinguisher through the extinguishing medium, lose considerable of their vitality and to overcome this disadvantage I have provided a conducting means for the gases, the said conducting means comprising a channel 51 connected to the inner receptacle 22 and communicating with the port 50; the said channel 51 extending longitudinally of the inner receptacle 22 and terminating adjacent the lower portion of the same. It will be apparent that upon inversion of the apparatus, the gases generated in the chamber 22 will move through the port 50 and up through the channel 51, as shown in Figure 2 of the drawings, the gases thus moving substantially out of contact with the fire extinguishing medium in the outer receptacle 10, and having exit from the channel 51 at a point above the level of the fire extinguishing medium when the device is inverted. For the purpose of preventing any of the fire extinguishing charge from moving up through the channel 51 and into the inner receptacle 22 responsive to pressure variations in outer receptacle 10, I provide a pressure equalizing port 52 in the channel 51.

The operation and use of my novel extinguisher will, in the main, be apparent from the above detailed description thereof. In assembling the parts the outer receptacle 10 is first charged with a fire extinguishing medium, such as a calcium chloride solution, the inner receptacle 22 being then inserted in position and hung from the top of the outer receptacle, as on the neck 14 thereof. The cartridge 26 is then dropped into position or this cartridge may be dropped into position in the inner receptacle 22 prior to the insertion of the same in the outer receptacle 10. It will be apparent that the cartridge 26 may be inserted with either end uppermost, this cartridge being fired from either end. The combined hand wheel 16 and firing pin 46 is then threaded onto the neck 14 and the extinguisher closed in this manner. If inspection or recharging the apparatus is desired the hand wheel is removed, simultaneously removing the firing pin 46, after which the inner tube or re-

ceptacle 22 may be removed and inverted, the cartridge 26 being removed in this manner without any chance of misfire. The apparatus is adapted for fire extinguishing use at all times and under all climatic conditions. The cartridge is effectively sealed as a unit and also within the inner receptacle 22, deterioration of the same during long storage use being effectively minimized. In time of fire the extinguisher is inverted in the ordinary manner, the inversion of the same to erect position causing the relatively heavy weighted cartridge 26 to forcibly gravitate from its inactive position to active position into cooperating with the firing pin 46. Cooperative impact between the firing pin 46 and the cartridge results in a breaking of an end diaphragm or plate 45 and results in the ignition of the firing equipment and the combustion of the firing powder and the fuses. The fuses burn relatively slowly, the generation of the gases taking place gradually, these gases escaping from the cartridge through the vents and cores in the weights, the gases of combustion filling the chamber 22 and moving out of the same through the port 50 and through the conducting channel 51 to the level of the fire extinguishing charge, the pressure exerted by these gases of combustion being operative to eject and expel the fire extinguishing charge in a continuous stream through the hose 20 and nozzle 21 onto the fire.

It will be apparent from the foregoing that I have provided an extinguisher extremely simple in construction and involving few and simple manufacturing steps in the production of the parts making up the extinguisher. It will be further apparent that by a simple adaptation, standard hand extinguishers may be converted into one of the type here involved, the adaptation simply including substitution of the usual inner tube by my novel gas generator system. It will be further apparent that the parts are so related as to afford simplicity of assembly and as to permit a maximum of safety during assembly, inspection and use and as to provide an extinguisher capable of efficient operation in time of fire.

I claim:

1. Fire extinguishing apparatus comprising containing means holding fire extinguishing charge, a gas generator comprising a movable cartridge containing non-liquid gas producing material adapted to be set off by impact due to cartridge movement on gravity actuation.

2. Fire extinguishing apparatus comprising containing means holding fire extinguishing charge, a gas generator adapted in time of fire to be set into activity for the generation of gases to exert operating pressure on the fire extinguishing charge to forcibly eject

the same from the containing means; said gas generator comprising a combustible cartridge adapted for movement in time of fire from an inactive to an active position, movement into active position being effective to start cartridge combustion and resulting gas generation.

3. Fire extinguishing apparatus comprising containing means holding fire extinguishing charge, a gas generator adapted to deliver gas to said containing means comprising a non-liquid gradually combustible cartridge ignitable by impact due to its movement, on gravity actuation, against a relatively fixed abutment.

4. Fire extinguishing apparatus comprising containing means holding fire extinguishing charge, a gas generator adapted to deliver gas to said containing means and comprising a non-liquid gradually combustible cartridge, firing means, and a fixed abutment, whereby the cartridge is ignited by impact due to its movement on gravity actuation.

25 5. A fire extinguishing device comprising a receptacle holding a fire extinguishing charge, a gas generator in the receptacle adapted in time of fire to be set into activity for the generation of gases to exert operating pressure on the fire extinguishing charge to forcibly eject the same from the receptacle; said gas generator comprising an inner receptacle and a combustible cartridge movably mounted in the inner receptacle and movable on gravity actuation in time of fire from an inactive to an active position, movement into active position being effective to start cartridge combustion and resulting gas generation.

40 6. A fire extinguishing device adapted to be set into activity by inversion, comprising an outer receptacle holding fire extinguishing charge, a separately made inner receptacle supported centrally in and by the other receptacle, a cartridge movable in said inner receptacle and containing slow burning non-liquid material, a fixed abutment and movable firing means in said inner receptacle, whereby gradual combustion of the said material is effected on impact resulting from cartridge movement.

55 7. A fire extinguishing device comprising an outer receptacle holding a fire extinguishing charge, a gas generator in the receptacle adapted in time of fire to be set into activity for the generation of gases to exert operating pressure on the fire extinguishing charge to forcibly eject the same from the receptacle, said gas generator comprising an inner receptacle having its lower end permanently closed and a cartridge containing non-liquid material movably mounted in the inner receptacle and movable in time of fire from an inactive to an active position, movement into active position being effective to

set off said non-liquid material and start gas generation; said inner receptacle comprising a chamber sealing the cartridge from the fire extinguishing charge in the outer receptacle, the said inner receptacle serving as a 70 gas chamber during active use of the device and being provided with port means communicating with the outer receptacle.

8. A fire extinguishing device adapted to be set into activity by inversion, comprising a receptacle holding a fire extinguishing charge, a gas generator for communication with the receptacle adapted in time of fire to be set into activity for the generation of gases to exert operating pressure on the fire extinguishing charge to forcibly eject the same from the receptacle; said gas generator comprising a combustible cartridge containing non-liquid slowly combustible material adapted for movement in time of fire upon inversion of the device from an inactive to an active position, movement into active position being effective to start cartridge combustion and resulting gas generation.

20 9. A fire extinguishing device adapted to be set into activity by inversion comprising a receptacle holding a fire extinguishing charge, a gas generator in communication with the receptacle adapted in time of fire to be set into activity for the generation of gases to exert operating pressure on the fire extinguishing charge to forcibly eject the same from the receptacle; said gas generator comprising a weighted combustible cartridge mounted to gravitate in time of fire upon inversion of the device from an inactive to an active position, movement into active position being effective to start cartridge combustion and resulting gas generation.

25 10. A fire extinguishing device adapted to be set into activity upon inversion, comprising an outer receptacle holding a fire extinguishing charge, a gas generator in the receptacle adapted in time of fire to be set into activity for the generation of gases to exert operating pressure on the fire extinguishing charge to forcibly eject the same from the receptacle; said gas generator comprising an inner receptacle extending substantially the length of the outer receptacle; and a cartridge movably mounted in the inner receptacle, normally located in the lower end thereof and movable upon inversion of the device from the said location to an active position, movement into active position being effective to start gas generation, the said inner receptacle comprising a gas chamber having port means communicating with the outer receptacle, said port means comprising a channel terminating adjacent opposite ends of said inner receptacle for conducting the generated gases from the gas chamber to a region adjacent the level of the fire extinguishing charge when the 110 device is inverted.

11. A fire extinguishing device comprising a receptacle holding a fire extinguishing charge, a gas generator for communication with the receptacle adapted in time of fire to be set into activity for the generation of gases to exert operating pressure on the fire extinguishing charge to forcibly eject the same from the receptacle; said gas generator comprising a weighted combustible cartridge adapted for movement in time of fire from an inactive to an active position, stationary means normally spaced from the cartridge and cooperating with the same in time of fire to set the cartridge into combustion activity, movement of the cartridge into active position resulting in cooperative impact between the cartridge and the stationary means effective to start gas generation.

12. A fire extinguishing device comprising a receptacle holding a fire extinguishing charge, a gas generator in the receptacle adapted in time of fire to be set into activity for the generation of gases to exert operating pressure on the fire extinguishing charge to forcibly eject the same from the receptacle, said gas generator comprising a cartridge provided with slow burning fuses and firing equipment mounted to gravitate in time of fire from an inactive to an active position, gravitation into active position being effective to fire the cartridge and start gas generation.

13. A fire extinguishing device comprising a receptacle holding a fire extinguishing charge, a gas generator for communication with the receptacle adapted in time of fire to be set into activity for the generation of gases to exert operating pressure on the fire extinguishing charge to forcibly eject the same from the receptacle; said gas generator comprising a cartridge provided with slow burning non-liquid material and firing equipment adapted for movement in time of fire from an inactive to an active position, stationary means normally spaced from the cartridge and cooperating with the same in time of fire to set the cartridge into activity, movement of the cartridge into active position resulting in cooperative impact between the cartridge and the stationary means effective to fire the cartridge and to start gas generation.

14. A fire extinguishing device adapted to be set into activity by inversion, comprising a receptacle holding a fire extinguishing charge, a gas generator in the receptacle adapted in time of fire to be set into activity for the generation of gases to exert operating pressure on the fire extinguishing charge to forcibly eject the same from the receptacle; said gas generator comprising a cartridge provided with slow burning fuses and firing equipment adapted for movement in time of fire upon inversion of the device from an inactive to an active position, stationary

means normally spaced from the cartridge and adapted for cooperation with the same in time of fire to set the cartridge into activity, movement of the cartridge upon inversion of the device effecting cooperative impact between the cartridge and the stationary means, this cooperation being effective to fire the cartridge and to start gas generation.

15. A fire extinguishing device adapted to be set into activity by inversion, comprising an outer receptacle holding a fire extinguishing charge, a separately made inner receptacle hung from the top of the outer receptacle, the said inner receptacle holding a movable gas producing cartridge, a closure for the outer receptacle removable without disturbing the inner receptacle and means connected to the closure for cooperating with the cartridge to set the same into activity upon inversion of the device.

16. A fire extinguishing device adapted to be set into activity by inversion, comprising an outer receptacle holding a fire extinguishing charge, a separately made inner receptacle hung from the top of the outer receptacle, the said inner receptacle holding a movable cartridge, a closure for the outer receptacle removable without disturbing the inner receptacle, and means connected to the closure for cooperating with the cartridge to set the same into activity upon inversion of the device; the said inner receptacle including means for restraining movement of the cartridge until substantially complete inversion of the device is effected.

17. A fire extinguishing device comprising an outer receptacle holding a fire extinguishing charge, a removable inner receptacle supported in and by the outer receptacle, the said inner receptacle holding a movable cartridge, a closure for the outer receptacle unconnected with said inner receptacle and means connected to the closure for cooperating with the cartridge to set the same into activity upon inversion of the device; the said inner receptacle comprising a chamber sealing the cartridge against the charge in the outer receptacle and including port means communicating with the said outer receptacle.

18. A fire extinguishing device comprising an outer receptacle holding a fire extinguishing charge, a removable inner receptacle hung from the top of the outer receptacle, the said inner receptacle holding a movable cartridge, a closure for the outer receptacle removable without disturbing the inner receptacle and means connected to the closure for cooperating with the cartridge to set the same into activity upon inversion of the device, the said inner receptacle being permanently closed at the bottom and comprising a chamber sealing the cartridge against the charge in the outer receptacle and including port means communicating with the said

outer receptacle; the said port means comprising an elongated channel for conducting the generated gases from the inner receptacle to a region adjacent the level of the charge 5 upon inversion of the device.

19. An inner receptacle for a fire extinguishing device comprising a tubular member having a closed bottom and being provided with a port adjacent its top and a 19 channel connected to said tubular member for communication with said port, the said channel extending longitudinally of the member and terminating in a region adjacent the bottom of the same; the said channel 15 being provided with an equalizing port adjacent its upper end.

20. A reversible cartridge, for use in fire extinguishing apparatus, having firing means at each end, and non-liquid combustible material between said means.

21. A reversible cartridge, for use in fire extinguishing apparatus, containing non-liquid combustible material, and firing means at each end of the cartridge movable with 25 reference to said material.

22. A reversible cartridge, for use in fire extinguishing apparatus, comprising a casting having frangible ends and containing non-liquid combustible material and firing 30 means between each frangible end and the combustion material.

23. A reversible cartridge, for use in fire extinguishing apparatus, having like weighted ends provided with firing means and non-35 liquid combustible material between them.

24. A cartridge for use with a fire extinguishing device comprising an enclosing shell, weight means and combustible fuse means located in the shell, and a firing equipment in the shell adapted to be set into activity 40 for firing the fuse means upon movement of the shell into contact with a firing pin.

25. A cartridge for use with a fire extinguishing device comprising an enclosing shell, combustible fuse means located in the shell, a hollow weight means located in the shell adjacent an end thereof and a firing 45 equipment in the core of said weight means; the said firing equipment being mounted adjacent an end of the shell and adapted to be set into activity for firing the fuse means on movement of the shell into contact with a firing pin.

26. A cartridge for use with a fire extinguishing device comprising an enclosing shell, combustible fuse means mounted 55 interiorly of the said shell, weighted elements located in the shell and at the opposite ends thereof and firing equipment also mounted in the shell and at opposing ends thereof whereby upon movement of the shell in either of opposing directions into contact with a firing pin, the firing equipment will be set into activity for firing the fuses.

27. A reversible cartridge for use with a

fire extinguishing device comprising an enclosing shell, combustible fuse means mounted interiorly of the said shell, hollow weighted elements located in the shell and at the opposite ends thereof and firing equipment mounted in the shell and in the cores of the said weighted elements whereby upon movement of the shell in either of opposing directions the firing equipment is adapted to be set into activity for firing the fuse 70 means.

28. A cartridge for use with a fire extinguishing device comprising an enclosing shell, weight means and combustible fuses located in the shell, and a firing equipment 80 in the shell adjacent an end thereof adapted to be set into activity for firing the fuses on movement of the shell into contact with a relatively fixed abutment, the shell being provided with a frangible plate at its end 85 overlying the firing equipment.

29. A reversible cartridge for use with a fire extinguishing device comprising an enclosing shell, combustible fuse means mounted interiorly of the said shell, hollow weighted elements located in the shell and at the opposite ends thereof and firing equipment mounted in the shell and in the cores of the weighted elements whereby upon movement of the shell in either of opposing directions into contact with a firing pin the firing equipment will be set into activity for firing the fuse means; the shell being provided at its ends with frangible plates 90 overlying the firing equipment.

30. A cartridge for use with a fire extinguishing device comprising an enclosing shell, weighted elements enclosed by the shell and located at opposed ends of the said shell, fuse means located within the shell and centrally thereof; the said fuse means comprising a plurality of combustion fuses each having an end exposed, screen elements located between the weights and the fuse means, loose firing powder confined by the screens on opposite ends of the fuses and firing equipment enclosed by the shell.

31. A cartridge for use with a fire extinguishing device comprising an enclosing shell, weighted elements enclosed by the shell and located at opposed ends of the said shell, fuse means located within the shell and centrally thereof; the said fuse means comprising a plurality of combustion fuses each having an end exposed, adjacent fuses having opposite ends exposed, screen elements located between the weights and the fuse means, loose firing powder confined by the screens on opposite ends of the fuses and firing equipment enclosed by the shell; the firing equipment being located within the cores of the weighted elements and frangible diaphragms on opposite ends of the shell and overlying the firing equipment.

32. A cartridge for use with a fire ex-

tinguishing device comprising an enclosing shell, weighted means and combustible fuses located in the shell, the combustible fuses being each provided with a wrapper, each 5 of the fuses having an end exposed, and firing equipment in the shell adjacent the exposed ends of the fuses adapted to be set into activity for firing the fuse on movement of the shell in the extinguisher into 10 contact with a firing pin.

33. A cartridge for use with a fire extinguishing device comprising an enclosing shell, weight means and combustible fuses located in the shell, and a firing equipment 15 in the shell adapted to be set into activity for firing the fuses on movement of the shell into contact with a firing pin, the weight means being provided with gas vents.

34. A cartridge for use with a fire extinguishing device comprising an enclosing shell, weighted elements enclosed by the shell, and located at opposed ends of the said shell, fuse means located within the shell and 20 centrally thereof; the said fuse means comprising a plurality of combustion fuses each 25

having an end exposed, screen elements located between the weights and the fuse means, loose firing powder confined by the screens on opposite ends of the fuses and firing equipment enclosed by the shell, the 30 weighted elements being provided with vent means.

35. A fire extinguishing device adapted to be set into activity by inversion, comprising an outer receptacle holding a fire extinguishing charge, a removable inner receptacle hung from the top of the outer receptacle, the said inner receptacle holding a movable cartridge provided with slow burning fuses and firing equipment, a closure 40 for the outer receptacle and means independent of the inner receptacle and located between the inner receptacle and the closure for cooperating with the cartridge to fire the same upon inversion of the device. 45

Signed at Columbus, in the county of Franklin and State of Ohio this 4th day of April A. D. 1921.

FREDERICK C. BARGAR.
